Primary Examiner — Selina Sikder(74) *Attorney, Agent, or Firm* — The Law Office of Patrick F. O'Reilly III, LLC(57) **CLAIM**

The ornamental design for a utility box cover, as shown and described.

DESCRIPTION

FIG. 1 is a top-front perspective view of a utility box cover showing my new design, wherein the cover lid is depicted in a closed position;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a bottom-front perspective view thereof;

FIG. 9 is another top-front perspective view thereof, wherein the cover lid is depicted in an open position; and,

FIG. 10 is another bottom-front perspective view thereof, wherein the cover lid is depicted in an open position.
